Primary Examiner — Mark A Goodwin*(74) Attorney, Agent, or Firm* — Carla Gannon Law(57) **CLAIM**

I claim the ornamental design for a carrying system for use with the roll bar of a vehicle, as shown and described.

DESCRIPTION

FIG. 1 is a front/side perspective view of the carrying system for use with the roll bar of a vehicle showing my new design; FIG. 2 is the front view of the carrying system of FIG. 1; FIG. 3 is the back view of the carrying system of FIG. 1; FIG. 4 is the top view of the carrying system of FIG. 1; FIG. 5 is the bottom view of the carrying system of FIG. 1; FIG. 6 is a side view of the carrying system of FIG. 1; FIG. 7 is the opposite side view of the carrying system of FIG. 6; and,

FIG. 8 is a front/side perspective view of the carrying system of FIG. 1 connected to a vehicle.

The broken lines showing the roll bar in FIGS. 1-8 are included for purposes of illustrating the carrying system in use, and form no part of the claimed invention.

The broken lines showing the vehicle and rake of FIG. 8 are included for purposes of illustrating the carrying system in use, and form no part of the claimed invention.
